7 Claims. (Cl. 74—469)

This application is a division of my United States Patent application Serial No. 836,636, for Winch for Hauling Trawl Nets, filed August 28, 1959, now abandoned, and pertains particularly to control mechanism for the driving motor of a winch such as disclosed in that application.

It is a principal object of the present invention to provide convenient and effective control mechanism for effecting rotation of the drum of such a winch and terminating such rotation.

Specifically, it is an object to provide control elements associated with guard rails for the winch, which not only provide convenient supports for the control elements, but which enable an operator to locate control elements readily while directing his attention elsewhere, which guard rails provide a convenient rest for the hand or the arm of the operator to reduce fatigue and to enable the control elements to be operated more accurately by the reaction of the operator's hand or arm from the guard rails, and which controls are located so that the operator can control the winch from different positions.

The control mechanism to which this invention pertains in particular includes control valve mechanism for a hydraulic motor which is actuated by a swingable control arm for moving a winch speed and direction controller. Such arm is swung by a link reciprocable by sliding movement of a direct control handle mounted on a guard rail at one side of the winch. To this sliding direct control handle is connected a remote control handle also mounted on the guard rail, but located at the opposite side of the winch in a position spaced lengthwise of the guard rail from the direct control handle.

FIGURE 1 is an aft top perspective of the winch, FIGURE 2 is a bottom perspective of a portion of the port end of the winch, and FIGURE 3 is a fragmentary port end elevation of the winch having parts broken away.

FIGURE 4 is a detail section through winch control mechanism taken on line 4—4 of FIGURE 3.

FIGURE 5 is a top perspective of components of the winch control mechanism and associated parts shown in exploded relationship.

FIGURE 6 is a diagram of the control mechanism component connections.

The winch to be controlled by the control mechanism of this invention is intended to be mounted on the after or amidships deck of a trawler. The port and starboard winch end frames 5 and 50 are connected by struts 51, as shown in FIGURE 1, and intermediate flanges 61 and 62 are secured to the drum 6 between the end flanges 42 and 63. The winch drum 6 is driven by motor M mounted on the port end frame 5. While such motor can be electric, it is preferably of the hydraulic type, and the control mechanism of the present invention is best adapted to control a motor of the hydraulic type at various speeds. As shown in FIGURE 6, a pump P can supply liquid under pressure to the speed and direction control valve 20 by which the flow of liquid to the winch driving motor M is controlled to flow at the desired speed through either a forward conduit or a reverse conduit depending on the direction in which it is desired to drive the winch.

As illustrated in the drawings, it is intended that the winch operation shall be controlled from its port end. It

is desirable, therefore, to protect the operator on a slippery, heaving deck from contact with the reel, lines or trawl and to enable the operator to maintain his position at the winch control station during heavy weather as well as to be able to control the winch quickly and effectively under such circumstances. For this purpose a guard rail 7 spanning the end of the winch and having curved end portions fore and aft of the winch which can be grasped readily is provided. Also, this guard rail serves as a convenient mounting structure for controls for the winch motor, which controls are desirably operable from positions adjacent to the forward side and adjacent to the aft side of the winch.

The winch motor must be of the variable speed type and preferably is also reversible. It is convenient for both the speed and direction of rotation of the motor M to be controlled by tilting the control arm 2, of a speed and direction controller, which can operate to actuate the motor in opposite directions by tilting it either fore or aft from a neutral upright position, and the speed of the motor can be controlled by the degree of tilt of such control arm from the upright position. Utilization of a control arm having such a control movement insures that the speed of the motor must be reduced progressively to zero before its direction of rotation is reversed, so as to avoid an abrupt reversal of stress in the motor and movable winch parts. The motor is positively connected to the winch drum 6 in all rotative positions.

While the upright control arm 2 could be grasped directly by the hand for manipulation to control the motor M, the speed and direction controller 20, which may include a regulating valve in the casing, on which the control arm is mounted could be placed in only one location, whereas it is desirable to be able to control operation of the winch from at least two locations, one adjacent to the aft portion of the winch, and one adjacent to the forward portion of the winch. Control mechanism is therefore provided to rock the control arm 2 from side to side, as viewed in FIGURE 3, by shifting fore or aft one or the other of the control handles 21 and 21a shown in FIGURE 1, which are located respectively adjacent to the aft side and the forward side of the winch. The direct control handle 21 is connected to the upper end of the control arm 2 by a generally horizontal link 22 having its end adjacent to the control arm received in a clevis notch in the upper end of such control arm and connected to it by a pivot pin 23. The opposite end of link 22 is journaled to swing relative to the handle 21 so that the connection between the handle and the control arm will not bind as the handle is reciprocated.

In the lower side of the tubular guard rail 7 is a slot 70 in which the upper portion of a slide 24 carrying the direct control handle may slide. A rod 22a extending lengthwise through the hollow of the tubular guard rail 55 7 has enlarged end portions 25 to one of which the slide 24 is secured by bolts 26. Another slide 24a is connected by bolts 26a to the enlargement 28 on the other end of the rod 22a. The upper portion of the slide 24a is received in a groove 70a in the bottom of the tubular guard rail 7, which is similar to the groove 70. Because of the interconnection of slides 24 and 24a by the rod 22a, reciprocation of either the direct control handle 21 or the remote control handle 21a will effect corresponding reciprocation of the other handle and consequently of the link 22, resulting in corresponding tilting of the swingable control arm 2.

It may be desirable to prevent the control valve arm 2 from being tilted in either direction from its neutral upright position, and for this purpose a latch clevis 27 may be mounted by pivot 28 on a yoke 29 secured to the end of the winch frame, as shown in FIGURES 2, 3 and 4. When the latch clevis is in its raised released position

of FIGURE 4, the control arm 2 can be swung freely by reciprocation of the control handles 21 and 21a and the link 22. When the latch clevis is swung downward into the position of FIGURE 4, however, so that its arms embrace the control arm, such control arm will be restrained from tilting in either direction from its neutral upright position. A cross pin 27 extending through the control arm will be engaged by the downwardly swung latch clevis arm to prevent swinging of such arms downward past the control arm 2 into a position inoperable to latch the control arm and secure it against motor-operating swinging movement.

In operation the guard rail 7, being firmly anchored to the winch both at its center and at its ends, as shown best in FIGURE 2, can be grasped by the winch operator as may be necessary to assist him in keeping his position adjacent to either the forward winch control handle 21a or the aft winch control handle 21. By resting his hand or forearm on the guard rail 7 either control handle 21 or 21a can be shifted accurately and steadily in one direction or the other to obtain the most desirable speed of winch operation under the particular circumstances. As a matter of fact, it will be evident from FIGURES 2 and 3 that the winch operator can actually grasp the guard rail 7 with one hand and with the thumb of the same hand can shift the control handle 21 or 21a in one direction or the other without releasing his grip on the guard rail. Also, the winch operator can locate either of the control handles quickly and easily while concentrating his attention and vision in an entirely different direction simply by sliding his hand in one direction or the other along the guard rail 7 until it comes into contact with the nearer control handle, which he can then engage and move still without distracting his attention from watching the trawl.

I claim as my invention:

1. Control mechanism for a trawl winch drum-driving motor speed-adjusting controller means, comprising a guard rail mounted on the winch, a control element carried by said guard rail and movable relative thereto, and trawl winch drum-driving motor controller means operatively connected to said control element and movable to effect a control operation by movement of said control element relative to said guard rail.

2. The control mechanism defined in claim 1, a second control element mounted on the guard rail spaced lengthwise thereof from the first control element and movable relative to the guard rail, the guard rail being hollow, and means extending through the guard rail hollow and operatively connecting the two control elements for conjoint corresponding movement relative to the guard rail for effecting a control movement of the winch drum-driving motor controller means.

3. The control mechanism defined in claim 1, a second control element mounted on the guard rail spaced lengthwise thereof from the first control element and mov-

able relative to the guard rail, and means operatively connecting the two control elements for conjoint corresponding movement relative to the guard rail for effecting a control movement of the winch drum-driving motor controller means.

4. The control mechanism defined in claim 1, and latch means operable to limit movement of the winch drum-driving motor controller means in a speed-increasing direction.

5. Control mechanism for a trawl winch drum-driving motor controller means, comprising a generally horizontal guard rail mounted on one end of the winch and extending in a direction transversely of the winch drum axis, a control handle, means slidably mounting said control handle on said guard rail in a position adjacent to said guard rail for shifting lengthwise of said guard rail, a tiltable winch drum driving motor control arm on the drum-driving motor controller means, and means connecting said control handle and said control arm for effecting tilting of said control arm by sliding of said control handle along said guard rail to effect a controlling operation of the drum-driving motor controller means.

6. The control mechanism defined in claim 5, in which the control handle is mounted on the guard rail at a location adjacent to one side of the winch, and a second control handle slidably mounted on the guard rail adjacent to the opposite side of the winch for shifting lengthwise of the guard rail and connected to the control arm for effecting movement of the control arm by sliding either control handle along the guard rail.

7. Control mechanism for the drum-driving motor of a trawl winch, comprising a hollow, generally horizontal guard rail mounted on one end of the winch, spaced outwardly therefrom and extending in a direction transversely of the winch drum axis, said guard rail being slotted lengthwise adjacent to opposite sides of the winch, two slides slidably received in said slotted guard rail at locations spaced lengthwise thereof and adjacent to opposite sides of the winch, a rod extending through the hollow of said guard rail and connecting said slides, a control handle mounted on each of said slides, each of said control handles being shiftable lengthwise of said guard rail to move said slides and said rod lengthwise of said guard rail, a tiltable winch drum-driving motor control arm, and means connecting said slides and said control arm for effecting tilting of said control arm by sliding of said slides, rod and control handles along said guard rail.
